UNITED STATES PATENT OFFICE.

MATTIE COLLIER LUCAS, OF LOUISVILLE, KENTUCKY.

CRIB ATTACHMENT FOR BEDS.

SPECIFICATION forming part of Letters Patent No. 608,523, dated August 2, 1898.

Application filed October 27, 1897. Serial No. 656,528. (No model.)

To all whom it may concern:

Be it known that I, MATTIE COLLIER LUCAS, a citizen of the United States, residing at Louisville, in the county of Jefferson and State 5 of Kentucky, have invented certain new and useful Improvements in Crib Attachments for Beds; and I do hereby declare the following to be a full, clear, and exact description of the invention, such as will enable others 10 skilled in the art to which it appertains to make and use the same.

This invention relates to improvements in bedsteads, and has more particular relation to bedstead attachments.

15 The invention consists of certain novel constructions, combinations, and arrangements of parts, all of which will be hereinafter more particularly set forth and claimed.

In the accompanying drawings, forming 20 part of this specification, Figure 1 represents a perspective view of a portion of a bedstead with my invention attached thereto, and Fig. 2 represents a central vertical section through my said improvement when in its doubled 25 position.

1 in the drawings represents the bedstead, and 2 my improved crib attachment. This latter comprises a frame portion 3, a spring-mattress 4, supporting-brackets 5, and side 30 and end guards 6 and 7, respectively. Said frame 3 may be of any desired construction and material, but is preferably given the rectangular form shown in the drawings. This frame is adapted to be supported in position by the 35 brackets 5, upon which it rests. Each of said brackets comprises a horizontal base portion 8, a hooked portion 9, and a bracing portion 10. Each of said horizontal portions 8 is provided at its outer end with an upwardly-projecting arm 11, provided near its upper end 40 with a journal-aperture 12, through which passes the lower bar of the guard 6, whereby the latter is secured movably in position. Said arms 11 also act as restraining means 45 for the frame 3 and prevent the same from sliding outward over the respective brackets. The hooks 9, which are formed upon the inner ends of the horizontal portions 8, also form restraining means for preventing the 50 inward movement of said frame 3. Each of

said hooks 9 is provided with an internal antifriction-roller 13, which is preferably covered with rubber and is adapted to rest upon the top of the bedstead-rail when the hooks 9 are applied in position over said rail. 55 Each of the bracing portions 10 is provided on its lower side with an adjustable slide 14, secured in position by a bolt 15, which passes through an elongated slot 16, formed in said slide and engaging said bracing portions. A 60 pendent stud 17 is mounted on the inner end of said slide and carries a rubber-bound roller 18, which latter is adapted to bear against the side of the bedstead-rail when my improved attachment is applied in position. The end 65 guards 7 are hinged at their respective outer ends to the guards 6, so that they may be doubled flat against the same when so desired to permit all of said guards being doubled down flat upon the spring-mattress 4, which 70 connects the respective side and end portions of the frame 3.

It will be observed from the foregoing description that my improved attachment may be instantly applied to a bedstead or detached 75 therefrom and securely held in position when applied thereto without any positive connection to the bedstead, such as would mar the finish of the side rails of the same. The engagement of the rubber-bound rollers with 80 the respective portions of the side rail effectively prevents any scratching or other injury to said rail and at the same time permits of the attachment being moved along the side rail with a minimum amount of friction. 85 When so desired, the respective guards 6 and 7 may be doubled flat upon the spring-mattress and the whole device disconnected from the bedstead by simply lifting the brackets, so that the hooks 9 disengage from the upper 90 portion of the side rail. The said guards 6 and 7 preferably comprise metallic frames covered by a suitable reticulated material; but I do not care to limit myself on this point, as any suitable construction of guard may be 95 employed.

Having thus described my invention, what I claim as new, and desire to secure by Letters Patent, is—

In a bedstead attachment, the combination 100

with a plurality of supporting-brackets each comprising a horizontal supporting portion, a hook portion, a pendent brace portion, and an adjustable roller-carrying slide mounted 5 on said brace portion, of a mattress-supporting frame mounted on said brackets, substantially as described.

In testimony whereof I affix my signature in presence of two witnesses.

MATTIE COLLIER LUCAS.
